C. H. ROLLASON

PAIL CLOSING DEVICE

Filed May 15, 1926

INVENTOR

Charles F. Rollason

BY *H. E. Deuel, Jr.*
ATTORNEY

UNITED STATES PATENT OFFICE.

CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE.

PAIL-CLOSING DEVICE.

Application filed May 15, 1926. Serial No. 109,246.

This invention relates broadly to pail-closing devices, and more specifically to an apparatus for attaching covers to pails.

The primary object of the invention is to provide a relatively simple hand-operated apparatus by means of which the usual lugs formed on pail covers may be conveniently turned into clinching relation to the rim-roll or bead of the pail.

10 A further object is to provide a device of the character mentioned which is light in weight, strong and durable and which requires the application of relatively slight force in the operation thereof.

15 In describing the invention in detail, reference is herein had to the accompanying drawings, in which—

Figure 1 is a top plan view of the invention with one of the operating levers shown 20 in section;

Figure 2 is a sectional elevation of the invention mounted upon a pail cover, the section being taken on line 2—2 of Fig. 1; and—

25 Figure 3 is an enlarged detail section.

Referring to said drawings, 1 indicates a circular base plate of a size and form adapted to seat upon a pail cover 2 at and adjacent to the upwardly pressed rim 3 of the latter. As herein shown for illustrative purposes, said base plate is of spider form and comprises an outer seating ring 1^a carried by arms 1^b which extend radially from a central hub portion 1^c. The ring 1^a is undercut annularly, as shown, to provide for seating thereof in substantially conformable relation to the cover rim 3. Rigidly carried by the hub portion 1^c is an upright post or standard 4, and vertically slidable upon said standard is a hub 5 to which are pivotally attached the upper ends of downwardly and outwardly inclined rods or bars 6 which have their lower ends pivotally attached to the ends of a plurality of levers 7. Said levers have formed upon their opposite ends

jaws 8 which are designed to be actuated into and out of inwardly bending relation to attaching lugs 3^a formed at relatively spaced intervals on the rim 3 of the cover. Each lever 7 is pivotally mounted slightly rearward of its jaw 8 upon the outer end of a radially extending arm 9 which is pivotally mounted at its opposite end upon the base plate 1, or upon a spider arm 1^b of said base

plate. Suitable resilient means is provided 55 whereby each of said pivoted arms is normally maintained in an upwardly swung position relative to the base plate, whereby the superposed parts of the structure are normally held in elevated position, as shown in Fig. 2 and as is shown in full lines in Fig. 3.

The resilient means herein disclosed comprises a spiral compression spring 10 which encircles a bolt 11 having a T-head 12 received in a recess provided therefor in the under side of the ring 1^a. Said bolt projects upward through a hole 13 provided therefor in said ring and through a tubular member 14 which has its lower end screwed into a threaded hole in the adjacent pivoted arm 70 9. A nut 15 adjustably mounted on the upper end of said bolt 11 normally occupies seated relation to the adjacent end of the tubular member 14; and the spring 10 rests at one end upon the ring 1^a and at its opposite end against said nut 15, or against a thimble 16 which underlies said nut and which is shiftable within said tubular member.

Formed on, or attached to, the vertically 80 shiftable hub 5 are two oppositely extending arms 17 to the outer ends of which are pivotally attached the lower ends of two links 18 which have their upper ends pivoted to operating levers 19 which normally occupy 85 substantially upright positions, having their lower ends pivotally mounted upon opposite ends of a crosshead 20 which is rigidly mounted upon the upper end portion of the standard 4. Each of the levers 19 is formed of two members 19^a which, adjacent to their upper ends, are inclined divergently and thence upwardly and which have their upper ends connected by a horizontally disposed pintle 21 having rotatable thereon a 90 wooden handle 22 by means of which the apparatus may be grasped by hand, as for operating the apparatus and also for carrying from place to place.

In practice, when it is desired to clinch 100 a pail cover 2 in place upon a pail 23, such cover is first disposed in seated position upon the cover with its lugs 3^a depending vertically over or past the rim-roll or bead 24 of the pail. The apparatus constituting 105 the invention is then applied in seated relation to the cover with the clinching jaws positioned in facing relation to said lugs 3^a.

Then, grasping the two handles, the operator swings the levers 19 outward and downward on their pivotal mountings, thereby, through the links 18, actuating the hub 5 to move 5 downwardly along or over the standard 4. This action, through the intermediacy of the bars 6, effects depression of the levers 7 against the yielding elevating force exerted upon the pivoted arms 9 by the compression 10, and simultaneously with such lowering movement the levers 6 are swung upon their pivotal mountings for gradually bending the lugs 3^a into underlying clinched relation to the rim-roll 24.

15 It is to be noted that the simultaneous in-swinging and lowering movements of the jaws 8, effected as above described, results in a gradual and close tucking of the lugs 3^a with respect to the rim-roll.

20 The springs 10, re-expanding following compression thereof, serve to elevate all of the various shiftable parts to their normal positions.

25 Due to the arrangement of the various levers and links whereby the clinching jaws are actuated, relatively slight force is required to effect the bending of the cover-attaching lugs into pail-closing position.

What is claimed is—

30 1. Apparatus for attaching covers on pails, comprising a base plate having a portion for seating upon the rim of the cover, pivoted arms carried by said plate, jaws pivoted upon said arms, link and lever mechanism for actuating said jaws into bending relation to the cover lugs, and means normally holding said arms, mechanism and jaws in positions wherein the last named of said elements are in non-engaging relation to said lugs.

35 2. Apparatus for attaching covers on pails, comprising a base plate having a portion for seating upon the rim of the cover, pivoted arms carried by said plate, jaws pivoted upon said arms, link and lever mech-

anism for actuating said jaws into bending relation to the cover lugs, and means interposed between the arms and the base plate normally holding said arms, said link and lever mechanism and said jaws in positions 50 wherein the last named of said elements are in non-engaging relation to said lugs.

3. Apparatus for attaching covers on pails, comprising a base plate having a portion for seating upon the rim of the cover, 55 a standard carried by said plate, a member slidable on said standard, pivoted supports carried by said plate, jaws pivoted on said supports, connections between said slidable member and said jaws, means normally 60 maintaining said parts in a position wherein the jaws are in non-engaging relation to the cover lugs, and lever mechanism whereby said slidable member is thrust downward for actuating said jaws to bend said lugs 65 inwardly.

4. In apparatus for attaching covers on pails, the combination with lug bending jaws and normally elevated mechanism for actuating said jaws, said mechanism including 70 a member which is vertically shiftable on said standard, of means for depressing said mechanism to effect jaw actuation, said means comprising oppositely swinging levers pivoted on said standard, and connections 75 between said levers and said shiftable member.

5. In apparatus for attaching covers on pails, the combination with lug bending jaws, mechanism for actuating said jaws, and resilient means normally maintaining 80 said mechanism in a position wherein the jaws are withdrawn with respect to the cover lugs, said mechanism including a vertically movable member, of a pair of pivoted levers 85 operatively connected to said member whereby the latter may be depressed.

In testimony whereof, I affix my signature.

CHARLES H. ROLLASON.
